United States Patent Office.

P. GENGBRE HUBERT, OF NEW YORK, N. Y.

Letters Patent No. 62,959, dated March 19, 1867.

CARTE DE VISITE EXHIBITOR.

The Schedule referred to in these Letters Patent and making part of the same.

TO ALL WHOM IT MAY CONCERN:

Be it known that I, P. GENGBRE HUBERT, of the city of New York, in the State of New York, have invented certain improvements in Carte De Visite Exhibitor; and I do hereby declare that the following is a full and exact description thereof, which will enable others skilled in the art to make and use the same, reference being had to the accompanying drawings, forming part of this specification, in which—

Figure 1 represents a front view of my improved carte de visite exhibitor when open and in the proper position for exhibiting the carte de visite placed therein; and

Figure 2 is a sectional elevation view of the same through its centre, and represents the instrument when closed and in the position it occupies when not in use.

The devices which have been made for exhibiting cartes de visite can be classified in three groups, viz, the albums or books in which the cards are placed and are exhibiting by turning over the leaves; the frames or stands in which one or more cards are placed to be hung up or placed on a shelf; and the boxes or frames provided with lens in which the cards are slipped one over the other so as to exhibit them one by one to the eye of the person looking at the cards through the lens. To this third group does my invention relate, and it consists in an improved and new exhibitor which I have called a Revolvicon; and which I will proceed to describe in detail.

Description.

A is a box or outside shell, made of any form, shape, or material desired, to be ornamental and convenient. *a a* is the lower part or rim of the box A, and B is the bottom of the same, which is made loose, and so fastened to the box A by suitable catches or hooks as to permit of the top A being lifted up away from the bottom B, when desirable. The box A is provided with a door, C, to which are fastened the eye-tube and lens D, and to which is suspended the reflector E, hanging freely, and provided with a suitable hole in or about its centre, through which the cartes de visites are to be looked at. In the centre of the bottom B is a hole through which the pin F is passed and in which it can revolve. G is a wheel or disk, fastened to the pin F, and by which the said pin F is caused to revolve when desired. H is a spool-shape piece, provided with bands of India rubber or other elastic material for retaining the cards in the position represented in my drawings, and allowing them to play freely as if they were hinged at the points *g g g g*, &c. The piece H has a hole through its whole length so that it can be slipped over the pin F, and it has at both ends notches, *h h h h*, in which the small pin *f* will fit, so that when the wheel G is turned the piece H will also be turned. To the bottom B are attached small uprights, M M'; to which are fixed suitable springs or catches, N N', adjustable at pleasure to regulate the position of the cards, as hereafter described. The whole apparatus is supported on three feet or legs P P and P', two of which are solid, and one of which has a slot in which is pivoted the leg R in such a manner that it can be brought out and support the revolvicon in the position represented in fig. 1, or that it can be turned under as represented in fig. 2, when the revolvicon is not in use.

Operation.

The fig. 2 of my drawings exhibits clearly the position of the cards in the revolvicon. Two cards are placed back to back between the elastic bands *h h h h*, and when the revolvicon is not in use and the door closed, the pictures are stored in a perfect manner. When it is desired to exhibit the pictures or cards stored in the revolvicon, the door C is opened to bring out the lens in focus, the movable leg R is turned out from under and the revolvicon is placed in the position represented in fig. 1. The reflector E, which was brought in close proximity to the door C, when the revolvicon was level and the door closed, is now standing in the position seen in fig. 1, for, as it hangs freely from the door, it will hang plumb at all times, and when the revolvicon is tilted, as in fig. 1, to place it in the proper position to exhibit the carte de visite placed therein, the reflector will take, of its own accord, the proper position for reflecting light into the revolvicon and on the card which is brought in sight. The catches N and N' are so regulated that when the revolvicon is tilted, (as in fig. 1,) the cards which are left in the space between the catches N and N' will fall by their own weight on the catch N', which will allow them to fall back and only retain two or three, and keep the top one in perfect focus with the lens D. As soon as the wheel G is turned, the catch N will let go a card which will fall on the one previously exhibited, and the

catch N' will let go one card back so the focusing will not be altered, and by turning the wheel G all the cards will be in turn brought forward and made to fall in focus of the lens D. When the whole of the cards from one side have been exhibited, the box A is lifted off, the piece H is turned upside down, and when the box A is replaced all the cards on the other side of the ones already seen will now fall in sight one at a time, as already described above. My revolvicon can be made to contain a larger or smaller number of cards.

What I claim as my invention, and desire to secure by Letters Patent of the United States, is—

1. The herein-described "revolvicon" in which cartes de visite are stored, as in fig. 2, and in which they are exhibited, as in fig. 1, by dropping in sight one after the other by their own gravitational force, arranged and operating as specified.
2. The combination of the piece H, pins F, and wheel G, with the carte de visite J J'', &c.
3. The combination and arrangement of the leg R, with the leg P', of the bottom B, to obtain the two positions of the instrument as specified.
4. The self-adjusting reflector E, arranged and operating as set forth.

P. GENGBRE HUBERT. [I. S.]
